(57) CLAIM

The ornamental design for a fitted plate lid, as shown and described.

DESCRIPTION

FIG. 1 is a bottom perspective view of a fitted plate lid, showing my new design;

FIG. 2 is a top plan view thereof;

FIG. 3 is a side elevation view thereof; and,

FIG. 4 is a bottom plan view thereof.

The broken lines illustrate portions of the fitted plate lid that form no part of the claimed design.
